HIGH PRECISION MEASURING MACHINE

Jacques Pettavel, Geneva, Switzerland, assignor to Societe
Genevoise d'Instruments de Physique

Filed Nov. 16, 1970, Ser. No. 25,995

Claims priority, application Switzerland May 19, 1970

Term of patent 14 years

Int. Cl. D10—04

U.S. Cl. D55—1

FIG. 1

FIG. 2

FIG. 3

FIG. 4

FIG. 5

FIG. 1 is a front perspective view showing the high precision measuring machine of the present invention;

FIG. 2 is a side perspective view from the left of FIG. 1;

FIG. 3 is a side perspective view from the right of FIG. 1;

FIG. 4 is a top perspective view; and

FIG. 5 is a rear perspective view of the machine.

I claim:

The ornamental design for a high precision measuring machine, as shown.
